PAPER FEEDING MACHINE

Fred Schwarzer, Pottstown, Pa., assignor to
American Business Systems, Philadelphia, Pa.

Application March 4, 1947, Serial No. 732,212

9 Claims. (Cl. 271—18)

1

This invention relates to a machine for feeding sheets of paper. An object of the invention is the provision of a machine for feeding sheets of paper as desired into typewriters, billing and similar machines in which the sheets of paper are discharged by the operation of a lever for moving a follower progressively toward the discharge end of a rack which carried the papers, the individual sheets being picked off a stack of papers on the supporting rack.

Another object of the invention is the provision of a machine for supplying individual sheets of paper from a stack on a rack in which the stack is moved progressively to a discharge end of the rack by a follower, the sheets of paper being picked off the stack by the ends of a pair of inwardly moving resilient fingers and then released as the fingers are withdrawn, the individual sheet being dropped into a slightly lowered position just before withdrawal from the stack while a succeeding sheet is held in elevated position by arms which are operated in timed relation with the inwardly moving fingers and the progressively shifting follower, the operation of the follower, the fingers and arms being effected by a single stroke of a manually actuated lever.

A further object of the invention is the provision of a machine for supplying sheets of paper individually to the platen by a typewriter by means of a progressively shifted follower on a rack which supports a stack of sheets of the paper, levers connected to the follower being actuated progressively by a spring-controlled shaft which in turn is rocked at angular increments by a toothed wheel through the medium of a reciprocating pawl, a second pawl retaining the wheel against reverse rotation by a spring and movable to an inoperative position for releasing the reciprocating pawl from the teeth of the wheel whereby the spring will reversely rotate the shaft and wheel and return the follower to its initial position, means actuated by a single stroke of a manually operated lever for picking individual sheets from the stack, said lever controlling simultaneously the movement of the reciprocating pawl.

The invention consists in the novel construction, arrangement and combinations of parts hereinafter more particularly described and claimed.

In the drawings:

Figure 1 is a front view in elevation of the machine for feeding sheets of paper.

Figure 2 is a rear view of the machine.

Figure 3 is a side view in elevation of said machine.

2

Figure 4 is a transverse vertical section of the machine taken along the line 4—4 of Figure 2.

Figure 5 is a fragmentary horizontal section of the main operating mechanism of the machine with the cover plate for said mechanism removed.

Figure 6 is a fragmentary side view showing the main operating mechanism for the sheet-shifting follower.

Figure 7 is a horizontal section taken substantially along line 7—7 of Figure 4 with the rearward levers omitted and showing the paper-picking means moved to operative position.

Figure 8 is a transverse vertical section taken along the line 8—8 of Figure 7.

Figure 9 is a front view in elevation of the lever and associated U-shaped member shown in Figure 8.

Figure 10 is a view in perspective of a filler block used in connection with the rack which supports the sheets of paper.

Figure 11 is a longitudinal vertical section of a manually operating device, taken along the line 11—11 of Figure 12.

Figure 12 is a plan view of the manually operating device shown in Figures 3 and 10 and

Figure 13 is a plan view of the rockable member illustrated in Figure 8 with parts broken away.

Referring more particularly to the drawings, 15 designates a standard which is U-shaped in cross section and which rises from a base member 16 adapted to be secured in any approved manner to a desk so the paper feeding machine may be in close association with the platen of a typewriter, not shown. A post 17 U-shaped in cross section, is fitted into the standard 15 and projects upwardly above the upper end of the said standard. A block 18 is connected to the standard. A block 19 is attached between the flanges of the post 17. An axle 20 is connected between the lower ends of the side flanges of said standard.

A lever 21 is pivoted at one end to a bracket 22 secured to the top of the post where a supporting block 23 is attached. Said block has a notch 24 received by the upper end of the post so that when a bolt 25 is removed said block and attachments may be removed. The lever 21 is forced upwardly by a spring 26 upon which pressure is adjusted by a bolt 27 carried by the block 19.

A link 30 is connected between an intermediate portion of the lever 21 and an eye 31 at the upper end of a rod 32 which extends downwardly in the standard 15 and through a stop 33 adjustably positioned on the rod by a bolt 34.

A U-shaped spring member 35 has a bight por-

tion received by a passage in an arm of a bell crank 36 pivoted on the axle 20. The free ends of the arms of said spring member are fastened to the stop 33.

A manually operating device 37 (Figs. 3, 10 and 11), is in a convenient position for the typist which is usually at the front of the desk 40. A clamp 41 is provided for retaining the device 37 in place and is connected to a housing 42. A lever 43 projects through a slot in the housing and has a finger piece 44 for manual actuation of the lever which is pivoted at 45 on the housing. A link 46 connects a free end of the lever 43 with a free end of a lever 47 pivoted at 48 on said housing. A link 49 is attached between the other free end of the lever 47 and a wire or rod 50. The link 49 passes through an opening in the housing 37 while the rod 50 passes through an opening in the lower end of the standard 15 and is attached to the lower free end of the bell crank 36 (Fig. 4).

A rack generally designated by the numeral 51 has a bottom member 52 which is attached to a block 53 that is in turn secured to the block 23 at the upper end of the post 17 (Figures 4 and 7). The bottom is U-shaped in cross section. Side plates 54 and 54-a are secured to the opposite ends of the bottom member in any approved manner. A brace bar 55 is bolted to in-turned flanges 57 on the side plates at the rear of the machine (Fig. 2). A front longitudinal plate 58 is bolted to out-turned flanges 59 on the front edges of the side plate (Fig. 1).

The follower 60 against which a stack of papers is placed is disposed between the side plates 54 of the rack 51. Spaced pairs of links 61 (Figures 2 and 4) have the inner ends pivoted on a U-shaped member 61-a to the back of the follower 60 while the outer ends are pivoted to the free ends of spaced levers 62 which have a bridging portion 62-a secured to the shaft 63 which has bearings in brackets 64 and 64-a secured to the flanges 57. The levers 62 and link 61 move the lower end of the follower toward the front end of the machine.

Levers 65 have their free ends pivotally connected to the outer ends of links 66 with the inner ends of the links having pivotal connection and a U-shaped member 66-a secured to the back of the follower 60. The levers 65 as shown in Figures 2 and 4 form the spaced arms of a U-shaped member which has a bridging portion 67 pivotally mounted on ears 68 attached to the upper flanged edge of the bar 55 (Figures 2 and 4). The links 66 are connected by a bridging member 69.

A lever 70 secured at one end to the bridging portion 67 projects downwardly and has pivotal connections with a depending link 71. A lever 72 has one end rigidly attached to the shaft 63 while the other end has pivotal connections with the lower end of the link 71 so that when the shaft 63 is rocked progressively, the follower 60 will be moved step-by-step toward the discharge end of the rack, with both the top and bottom of the follower being shifted simultaneously the same distance. The levers 65 and 70 in effect form a bell crank while the levers 62 and 72 also form a bell-crank.

The lower ends of the sheet of paper are supported by the upper free edges of a pair of spaced parallel flanges 75 on a U-shaped member 76 which has its bridging portion secured by bolts 77 to the bottom member 52 of the rack. The lower edge of the follower 60 rides on and is supported by said flange (Figures 4 and 7). A pair

of arms 78 and 79 are rigid with a shaft 80 mounted in bearings in the spaced flanges 75 intermediate the ends of the member 76. The arm 79 extends rearwardly from the shaft 80 and has a downwardly bent free end 81 located in a slot 82 at the rear end of the member 76. A ball 83 is secured to said free end. The inner free ends of the arms 78 and 79 project beyond an upstanding lip 84 at the end of the member 76. This lip has a slot 85 for a purpose which will be presently explained.

A lever 86 projecting from a rock shaft 87 is engaged by a downwardly projecting finger 88 on the arm 78. When the arm 78 is lowered by the weight of a sheet rested thereon, the lever 86 is lowered. It will be noted that the front ends (Figures 7 and 8) of the flanges 75 are cut-away at 89, to form a lower edge portion so that the lower end of the sheet of paper will drop lower than the normal free edges of the flanges 75 upon which said sheet has been supported during the forward movement of the follower 60. The portions 89 are substantially in the same plane as the upper surfaces of the inner portions of the arms 78 and 79 when said arms have been lowered.

Referring to Figures 5 and 6, mechanism is illustrated for rotating the shaft 63 upon which a coil spring 90 is wound. One end 91 of said spring rests against the bracket 64 while the other end 92 is secured in a passage in a collar 93 rigid with a gear 94 which is attached to the shaft 63. A small gear 95 meshes with the gear 94. The gear 95 and a large gear 96 are fixed to a shaft 97 mounted in bearings in a bar 98 and a plate 99 attached to the adjacent side plate 54 of the rack 51. The gears 94 and 95 and the shaft 63 are revolved when the gear 96 is revolved. A pawl 100 engages the teeth of the gear 96 and prevents reverse rotation of said gear by the coil spring 90 until the pawl is released by the lever 101 which is pivoted at 102 on the plate. A spring 103 maintains the pawl 100 in engagement with the teeth of the gear 96.

An oscillating pawl 104 engages the teeth of the gear 96 and is pivoted at 105 on a lever 106 which is connected at one end by a link 107 with an intermediate portion of an arm 108 by a saddle 109. The lever 106 has the other end pivoted at 110 on the plate 99. A finger 111 on the pawl 104 is adapted to engage a cam surface 112 on the pawl 104 for forcing the last mentioned pawl out of engagement with the teeth of the gear 96. A pin 113 on the plate 99 limits the movement of the pawl 104 so that the pawl 104 will not be placed in a position where it will not fall by gravity into the teeth of the gear 96 when released.

One end of the arm 108 is rigidly attached to one end of a shaft 115. The other end of said arm is connected with one end of a rod 116. The rod 116 and shaft 115 run transversely of the front end of the machine. A link 120 has one end pivotally connected with the rod 116 while the other end of said link is pivoted to the front end of the lever 21 at the middle of said machine. A curved arm 121 has the front end rigid with the other end of the shaft 115. The other or rear end of said arm is pivoted on the other end of the rod 116. Thus it will be seen that when the lever 36 is rocked, the lever 21 and the shaft 115 will be rocked and the pawl 104 will be shifted for progressively rotating the toothed wheel 96.

The shaft 115 (Fig. 8) has a bearing at one end in the plate 99 while the other end of the

shaft has a bearing in a projection 125 of the side plate 54—a. A U-shaped lever 126 has a bridging portion 127 and parallel legs 127—a which have the lower ends thereof secured at 128 to the shaft 115. The upper free end of each leg has an inturned flange 129 from which extends a vertical finger 130.

A U-shaped member 131 (Figures 7, 8 and 9) has a top or bridging portion 132 and depending legs 133 which are pivoted at the lower ends on the shaft 115 at each side of the legs 127—a of the lever 126. The bridging member at the outer end is provided with an upstanding flange 134 which is adjacent a vertical flange 135 on an adjustable member 136 in contact with the under surface of the member 132. A flange 137 at the inner end of the member 136 is adjacent the inner end of the bridging member 132 and is provided with a pair of passages 138 for a purpose which will be explained presently.

A device is provided in connection with the lever 126 and the U-shaped member 131 for the positive removal of sheets of paper or folded paper from the rack. The device includes spring arms 140 of a V-shaped member 141, said arms being connected together by a bight portion 142. The member 141 rests on the top 132 of the U-shaped member 131 with arms being received by the elongated passages 138 in the flange 137. The free ends 143 are pointed and directed toward each other, as shown in Figure 12.

The bridging member 132 has a pair of elongated parallel passages 144 (Fig. 13) which are aligned with similar parallel passages 144—a in the slide 136 (Fig. 8). The fingers 130 on the lever 127 project upwardly through said aligned passages 144 and 144—a and engage the spring arms 140 of the V-shaped member 141, for a purpose to be presently defined.

A block 145 is mounted on the top 132 and held in a predetermined position by a bolt 146 received by a passage 147 in said block and threaded into a passage in the slide 136. Said bolt is also received by an enlarged opening 132—a in the member 132 of the U-shaped member 131. The bottom face of the block 145 has a lug 148 which is embraced by the bight portion 142 of the member 141 while said bight portion is received by a groove 149 partially surrounding the lug 148. The passage 147 has a diameter sufficiently large to permit adjustment of the block 145 toward or away from the flange 137. A head 150 on the bolt 146 is adapted to engage the upper face of the block for securing the block in an adjusted position after the pointed ends 143 of the arms 140 have been placed the proper distance from the flange 137 for gripping paper on the rack 51.

The block 145 is moved toward or away from the flange 137 by a wheel 151 which has a central bore threaded onto a screw 152 secured to the flange 135 and to the block 145. The wheel has a portion received neatly by a passage 153 in the slide 136 while said wheel is disposed in a slot 154 in the top or bridging portion 132 of the U-shaped member 131. The slot 154 is sufficiently wide to permit the wheel to move back and forth in said slot. An opening 155 in the flange 134 forms a bearing for the screw 152. When the wheel 151 is rotated on the screw 152 said wheel is moved longitudinally of the top member 132 after the bolt has been loosened by the head 150 for shifting the slide 136 longitudinally along the member 132 for adjustably positioning the pointed ends toward or away from the opening 85 in the flange 84 on the U-shaped

member 16 (Fig. 7). In other words, the flange 137 on the slide 136 is adjusted relative to the pointed ends 143 of the spring member 141.

A crank 160 (Figs. 5 and 6) secured to one end of the rock shaft 87 projects through an opening 161 in the side wall 54 of the rack 51 and an annular opening 162 in the plate 99. Said crank is in engagement with the edge 112 of the pawl 104. When a number of manifolds is placed on the rack 51 and said manifolds are progressively moved forwardly towards the discharge end of the rack, a manifold will be shifted onto the free ends of the arms 78 and 79 before being picked off the arms by the pointed ends 143 of the spring arms 140 and the weight of the manifold will be sufficient to depress said ends of the arms and the lever 86 so that the shaft 87 will be rocked causing the crank 160 to force the pawl 104 to move in the direction indicated by the arrow in Figure 6 and to free said pawl from the teeth of wheel 96. Thus continued operation of the lever 36 will not move the wheel 96 nor the follower 60, until the manifold has been removed from the rack by the pointed ends or picking fingers 143.

As shown in Figure 6, the wheel 96 has a blank portion 165 from which teeth have been removed so that when the retaining pawl 100 reached said portion the wheel 96 remains inoperative. At this time, the follower 60 will have shifted all of the sheets of paper or manifolds off the rack. The pawl 100 is moved away from the wheel 96 until the arm 111 forces the operating pawl out of engagement with the teeth of the wheel 96 whence the spring 90 will return said wheel to its normal operating position. If the spring needs tightening the collar 93 may be released by releasing a set screw 93—a. The collar may be rotated until the spring has been wound sufficiently on the shaft 63.

An apron 166 (Figures 1, 2 and 3) has depending ears 167 at the upper end thereof with lateral pins 168 on the ears passing through perforations in the side walls 54 and 54—a of the rack 51. Nuts 169 are threaded onto the pins for adjustably positioning the apron so that the sheets of paper or manifolds will be directed properly into the typewriter.

A guide 170 L-shaped in cross section (Figures 1, 2, 3) is secured to a block 171 and provided with a slot 172 receiving the lower edge of the apron 166. A set screw 173 is threaded into a passage in the block for attaching the guide in an adjusted position along the lower edge of the apron. The free edge of one flange 174 of the guide is in engagement with the outer surface of the apron while the other flange 175 is spaced from the apron. The flanges cooperate with the apron to form a groove at one side edge of the apron for guiding papers or manifolds into the typewriter.

Fillers 176 (Figures 1 and 10) are attached removably to the side walls 54 and 54—a of the rack 51 when narrower sheets of paper or manifolds are employed. In this connection, it may be stated that the guide 170 is adjusted accordingly along the apron to take care of the sheets of less width. Each side wall has a bayonet slot 177 to receive a headed pin or bolt 178 mounted on the filler. The periphery of each filler is so designed that said filler will have a neat fit in the opposite side walls 54 and 54—a of the rack.

A cover plate 179 houses the mechanism illustrated in Figure 6. Said plate is secured removably in place by a bolt 180 threaded into a perforation 75 in the flange 84 on the U-shaped

ration in the side wall 54 of the rack 51. The nut 169 exterior of the cover plate 179 cooperates with the bolt 180 for retaining said plate in position. The threaded pin 168 extends through a perforation in the cover plate.

The lever 126 and U-shaped member 131 (Fig. 8) are enclosed within a housing 181 (Figures 1 and 3) formed integrally with the front plate 58 and projects outwardly therefrom. A hinged cover 182 closes the top of the housing and may be raised when it is desired to adjust the position of the gripping fingers 143 (Fig. 13) relative to the flange 137.

Arms 185 are secured adjustably to the upper rear face of the follower 60 by bolts 186. The arms are placed normally in overlapping relation, as shown in Figure 2, but may be raised to vertical positions for supporting papers or manifolds which project too far above the upper end of the follower 60 and which would tend to bend rearwardly without such support.

Referring more particularly to Figures 2 and 4, it will be seen that the post 17 is not only readily removable from the standard 15 but is mounted adjustably within said standard. An L-shaped member 190 has a flange 191 resting on the top of the block 18 while the other flange 192 is in contact with the rear wall of said block. The flanges 191 and 192 extend across the full width of the standard 15 so that inclined edges 193 of the parallel flanges on the post 17 will engage the opposite ends of the flange 192 on the member 190. A winged bolt 194 threaded into a transverse passage in the block with the free end of said bolt being in engagement with the flanges 192 of the member 190. The post 17 is in its lowest position in Figure 4 and is held in such position by the flange 192 engaging the inclined edges 193 of the post. Said post may be elevated and retained in such position by screwing the bolt 194 inwardly for forcing the flange 192 against the edges 193.

The operation of my device is as follows:

The follower 60 must be placed in the position shown in Figure 4. This is accomplished by pressing on the lever 101 (Figure 6) whence the pawl 100 will be freed from the teeth of the wheel 96 and the finger 111 will force the pawl 104 away from the teeth of said wheel. The spring 90 will reversely rotate the wheel 96 and return the follower to the position shown in Figure 4 by the rotation of the shaft 63 which actuates the groups of levers 65—66 and 61—62. The manifolds or sheets of paper are then placed upon the rack with the lower edges resting on the upturned flanges 75. The apron 166 is adjustably positioned so that said apron will guide the manifolds into a position against the platen of the typewriter.

It is to be borne in mind that the rack 51 will be filled with a stack of papers or manifolds which are discharged individually from the rack for reception by the typewriter and the leading manifold or sheet of paper is picked off the rack at the discharge end thereof when said manifold or paper is moved onto the levers or arms 78 and 79 at the reduced portions 89 of the flanges 75.

Wherever the word "paper" is used in the description and claims, it is intended to include a manifold or a sheet of paper. The leading paper referred to above denotes that paper on the rack which faces the jaws 143 (Figure 13) and which is in the position where it will be withdrawn from the rack at the next operation of the lever 36 (Figure 4).

It will be necessary to adjust the stop 33 on the

swinging rod 32 to a position where the throw of the lever 36 will cause the pawl 104 (Figure 6) to engage successively one tooth at each rocking of said lever or the adjustment may cause the pawl to engage successively every second or third tooth. The adjustment of the stop depends upon the thickness of the folders, manifolds, or sheets of paper. When single sheets of paper are placed in the rack the pawl 104 will revolve the wheel 96 by engaging successively single teeth while the thicker folders or manifold will require a greater angular step-by-step rotation of the wheel.

The rack 51 of the machine having been supplied with a stack of papers (Figure 4) and the proper adjustment of the stop 33 having been made, the machine is in condition to supply papers as desired to the platen of the typewriter. The lever 43 (Figures 3 and 11) is manually operated for actuating the levers 36 and 21 (Figures 2 and 4) whereby the shaft 115 will be rocked by the curved arm 121, rod 116 and link 120. At the same time the arm 108 is also rocked so that the links 107 and 106 will move the pawl 104 back and forth for rotating the wheel 96 step-by-step.

Actuation of the wheel 96 causes rotation of the shaft 63 through the intervention of the gears 95 and 94 while progressively winding the spring 93 (Fig. 5). As the shaft 63 is rotated step-by-step the follower 60 is moved progressively through the rack 51 until the leading paper drops from the upper edges of the flanges 75 to the portions 89 of the flanges and onto the arms 78 and 79 (Figure 8), from whence the papers are picked off by the jaws 143 (Figure 13).

At each incremental movement of the follower 60 in the rack, the lever 125 (Figures 4 and 8) rocks the U-shaped member 131, the flange 137 and the projecting jaws 143 into the dotted line position shown in Figure 8 with said flange in engagement with the flange 84 at the discharge end of the rack. The jaws 143 are projected through the passage 85 in the flange 84. However, the jaws will not grip the leading paper unless the lower end of said paper has been seated on the reduced portions 89 of the flanges 75. When said leading paper drops onto portions 89 of said flanges, the flange 137 will press the lower end of the paper against the flange 84 so that the jaws 143 will move through said paper and be clamped thereon, as will be presently described.

The spring arms 140 (Figures 8 and 13) will resist forward movement of the fingers 130 in the slots 144 sufficiently to cause the lever to move the U-shaped member 131 and the flange 137 into a position between the members 89 so that the flange 137 on said U-shaped member will engage the bottom of the leading paper and the jaws 143 will penetrate said paper. The shaft 115, however, has not as yet completed its rocking movement so that during the final angular rotation of said shaft, the fingers 130 on the lever 126 will force their way through the aligned slots 144 and 144—a against the tension of the spring arms 140 and thus move the arms and the jaws 143 toward each other, thereby causing the jaws to grip the leading paper.

The spring 26 (Figures 2 and 4) will return the lever 21 and associated element to the normal inoperative positions when the lever 43 (Figure 3) is released, so that the rock shaft 115 and attached lever 126 will return to their inoperative positions. During the return of the lever 126, the jaws 143 will pull the leading paper from the

rack and because of the tension of the spring arms 140 the fingers 130 will move rearwardly in the slots 144 thereby releasing the spring arms 140 (Figure 13), while the jaws 143 are unclamped from the paper and said paper will fall and be guided by the apron 166 and the member 170 into engagement with the platen of the typewriter.

The blank space 165 on the wheel 96 (Figure 6) is so arranged that when the final paper in the rack reaches the discharge end and is withdrawn, the space 165 when it reaches the pawls 100 and 104 will stop any further step-by-step movement of the follower and the rock shaft 115. At this time the pawl 100 is rocked away from the wheel 96 when the finger 111 will free the pawl 104 from said wheel to permit the spring 90 to return the follower 60 to its initial position.

I claim:

1. A paper feeding machine comprising a rack having a discharge end, means moving papers through the rack to the discharge end, means for picking the leading paper from the rack, said means including a rock shaft, a U-shaped member having the legs thereof pivoted on said shaft, a lever located within the U-shaped member and secured to the shaft, a slide mounted at the under face of the bridging portion of the U-shaped member and provided with an up-standing flange facing the discharge end of the rack, said flange having spaced openings, a V-shaped paper picking element having spring arms mounted on the bridging portion with jaws on the free ends and curved toward each other, said jaws projecting through the openings to grip the paper, means securing the opposite ends of the arms to the bridging portion, means adjustably positioning the slide on the bridging portion for varying the distance between the jaws on the spring arms and the flange, co-operating means causing rocking of the shaft and lever for projecting the jaws into gripping relation with leading paper and means for causing the moving means for the papers to shift said papers to the discharge end of the rack.

2. A paper feeding machine comprising a rack having a discharge end, means moving papers through the rack to the discharge end, means for picking the leading paper from the rack, said means including a rock shaft, a U-shaped member having the legs thereof pivoted on said shaft, a lever located within the U-shaped member and secured to the shaft, a V-shaped paper picking element having spring arms, the free ends of said arms being pointed and curved toward each other, the U-shaped member having a bridging portion upon which the bight portion of the V-shaped element is secured, a lever within the U-shaped member being secured to the shaft, said bridging portion having parallel slots therein below the spring arms, fingers on the lever projecting upwardly through the slots and in engagement with the spring arms, means rocking the shaft and lever, the spring arms acting on the fingers causing the U-shaped member to be rocked with the lever until the pointed ends of the arms pierce the leading paper, continued rocking of the lever moving the fingers along the slots and forcing the arms toward each other so that the curved pointed ends will firmly grip the paper, means returning the lever and fingers for withdrawing the paper from the rack while the spring arms return to inoperative positions for releasing the paper, and means operating the

moving means for the papers simultaneously with the rocking of the lever.

3. A paper feeding machine comprising a rack having a discharge end, means moving papers through the rack to the discharge end, means for picking the leading paper from the rack, said means including a rock shaft, a U-shaped member having the legs thereof pivoted on said shaft, a lever located within the U-shaped member and secured to the shaft, the U-shaped member having a bridging portion at the upper ends of the legs, flared spring arms having the inner ends secured to the top of the bridging portion, the free ends of said arms being provided with paper gripping jaws, said bridging portion having spaced elongated slots below the arms, fingers on the lever projecting through said slots, each finger engaging a spring arm so that when the lever is rocked the fingers acting against the spring arms will rock the U-shaped member until the jaws on the arms will grip the leading paper on the rack, continued rocking of the lever will cause the finger to move in the slots and force the arms and jaws toward each other, means for rocking the lever toward the rack, means returning the lever and fingers to inoperative positions for releasing the spring arms and the jaws from the paper, the returning U-shaped member withdrawing the leading paper from the rack, and means operating the moving means for the papers on the rack simultaneously with the rocking of the lever.

4. A paper feeding machine comprising a rack having a discharge end, means for moving paper through the rack to the discharge end, a rock shaft, a lever secured to said shaft, a rockable means pivoted on the shaft and movable into contact with the leading paper on the rack at the discharge end by the lever, jaws on the rockable means adapted to grip leading paper, means on the lever for causing the jaws to grip said paper, means for rocking the shaft to move the rockable means onto the paper, means returning the lever and rockable means to an inoperative position for withdrawing the leading paper from the rack, while causing the means on the lever to release the jaws from the paper and means operating the paper-moving means in the rack, said last-mentioned means being operatively connected with said rockable means and being movable in timed relation therewith.

5. In a paper feeding machine, means for moving a stack of papers through a rack comprising a follower in the rack and inclined at an angle to the vertical, a shaft mounted on the rack, a bell crank secured to the shaft, a link having pivotal connections between one arm of said bell-crank and the bottom of the follower, a second bell-crank pivoted on the follower adjacent the top, a link pivotally connected between the follower and the free end of one arm of the second bell crank, a link connecting the other arms of the bell-cranks, a toothed wheel mounted on the rack, operative connections between said wheel and the shaft, an oscillating pawl engaging the wheel for causing step-by-step rotation of the wheel, a spring connected between the shaft and the rack being wound when the shaft is rotated, a pawl retaining the wheel against reverse rotation by the spring, and means for oscillating the first pawl for rotating the wheel and causing shifting of the follower through the rack toward the discharge end.

6. In a paper feeding machine, means for moving a stack of papers through a rack comprising a follower in the rack and inclined at an angle

11

to the vertical, a shaft mounted on the rack; a bell crank secured to the shaft having pivotal connections between one arm of said bell-crank and the bottom of the follower, a second bell-crank pivoted on the follower adjacent the top, a link pivotally connected between the follower and the free end of one arm of the second bell crank, a link connecting the other arms of the bell-cranks, a toothed wheel mounted on the rack, operative connections between said wheel and the shaft, an oscillating pawl engaging the wheel for causing step-by-step rotation of the wheel, a spring connected between the shaft and the rack being wound when the shaft is rotated, a pawl retaining the wheel against reverse rotation by the spring, means for oscillating the first pawl for rotating the wheel and causing shifting of the follower through the rack toward the discharge end, and a finger on the second pawl adjacent the first pawl causing the finger to move the first pawl out of engagement with the wheel so that the spring will reversely rotate the shaft and return the follower to its initial position.

7. In a paper feeding machine, means for moving a stack of papers through a rack comprising a follower in the rack and inclined at an angle to the vertical, a shaft mounted on the rack; a bell crank secured to the shaft, a link having pivotal connections between one arm of said bell-crank and the bottom of the follower, a second bell-crank pivoted on the follower adjacent the top, a link pivotally connected between the follower and the free end of one arm of the second bell crank, a link connecting the other arms of the bell-cranks, a toothed wheel mounted on the rack, operative connections between said wheel and the shaft, an oscillating pawl engaging the wheel for causing step-by-step rotation of the wheel, a spring connected between the shaft and the rack being wound when the shaft is rotated, a pawl retaining the wheel against reverse rotation by the spring, an actuating lever, operative connections between the actuating lever and the oscillating pawl for causing step-by-step rotation of the wheel and the follower, and means operated by the second pawl for throwing the oscillating pawl away from the wheel so that the spring will reversely rotate the shaft and return the follower to its initial position.

8. In a paper feeding machine having a rack for supporting a plurality of papers adapted to

12

be withdrawn singly from said rack, means for withdrawing the papers from the rack, comprising a rock shaft, a lever secured at one end to said shaft, a rockable means pivoted on the shaft and operated by the lever, jaws on the rockable means adapted to grip the leading sheet on the rack, cooperating means on the lever and rockable means for causing the jaws to grip the leading paper when said jaws are moved into engagement with said leading paper by the lever, means causing rocking of the shaft and lever, and means returning the lever and rockable member to an inoperative position.

9. A paper feeding machine comprising a rack having a discharge end, spaced upstanding flanges on said rack for supporting the lower ends of the papers arranged in stack formation edgewise, the flanges at the discharge end being cut away to provide paper-supporting edges at a lower level, a rock arm adjacent the cut-away portions of the flanges and disposed normally above the upper edges of said cut-away portions, means for shifting the follower and the papers in incremental stages toward the discharge end so that the leading paper will be moved onto said rock arm, the weight of said paper depressing said arm, means for picking the leading paper from the rack, means oscillatable about the common shaft for operating said shifting means and said picking means in timed relation to advance the paper to said supporting edges and to move the picking means into operative relation with the leading paper, means returning said picking means to an inoperative position while withdrawing the leading paper from said rack, and means operated by said rock arm when depressed for rendering the shifting means for the follower inoperative until the leading paper is withdrawn from said rock arm.
